UNITED STATES PATENT OFFICE.

WILLIAM E. SCARLETT, OF EAST LYNN, MASSACHUSETTS, ASSIGNOR TO HAMEL SHOE MACHINERY COMPANY, OF LYNN, MASSACHUSETTS, A CORPORATION OF MASSACHUSETTS.

HEEL-NAILING MACHINE.

1,165,364.

Specification of Letters Patent.

Patented Dec. 21, 1915.

Original application filed May 2, 1914, Serial No. 836,014. Divided and this application filed April 10, 1915. Serial No. 20,523.

To all whom it may concern:

Be it known that I, WILLIAM E. SCARLETT, a citizen of the United States, and resident of East Lynn, county of Essex, Commonwealth of Massachusetts, have invented an Improvement in Heel-Nailing Machines, of which the following description, in connection with the accompanying drawings, is a specification, like characters on the drawings representing like parts in each of the several views.

This invention has for its object the production of a heel nailing machine such as is shown and described in my prior application, Serial No. 836,014, filed May 2, 1914, of which this present application is a division.

In the nailing of heels onto shoes as ordinarily carried out in power machines, trouble has been frequently experienced with the crushing and breaking down of the lasts under the thrust of the nailing head, this being due to the fact that the usual nailing machines heretofore in use have not had any adequate means for gaging and accurately determining the position of the last with reference to the height of the heel and the final limit of the stroke of the power head for the various different styles of heels and kinds of lasts.

The prime object of the present invention is to provide means whereby any given last with any selected style and height of heel may be quickly and conveniently positioned and clamped in accurate and definitely known relation to the stroke of the power head whereby the extent of compression by the power head in pricking and nailing operations can be definitely determined, and liability of undue pressure, which would be liable to crush the last, avoided.

The above features of the invention will be better understood from the following detailed description taken in connection with the accompanying drawings, and will be thereafter pointed out in the appended claims.

Referring to the drawings: Figure 1 shows in side elevation the operative parts of a heel nailing machine constructed in accordance with my invention; and Fig. 2 is a fragmentary detail showing my improved two-step locking device as seen from the front of the machine.

At the rear of a suitable stand or base 1 is

fixed a block 2 from which rises a guide column 3 on which is slidably fitted a depending sleeve 4 of a head 5 from the front of which projects the usual nailing plate and nail templet guide 6. The vertical movement of the head 5 is controlled by a hand lever 7 fulcrumed at 8 near the rear of the machine and extending toward the front thereof, this lever being connected by a link 9 with the depending sleeve 4 of the head 5. The head 5 is normally held yieldingly at its upper limit of movement by a stout coil spring 10 acting between the top of the column 3 and a recessed seat in the head 5. The power drive mechanism, a part of which is indicated at 11, may have the usual prick head and a drive head 12 operable in the usual manner.

In accordance with my invention I provide means whereby the head 5 bearing the nailing plate 6 may be locked in a definite preliminary lowered position where the nailing plate is adapted to serve as a backing to permit the heel to be clamped in place on the shoe under the action of the jack as presently described; this preliminary locking of the head 5 being so arranged with reference to the range of movement of the power head that, as the power head descends for the pricking operation, the head is forced farther down a predetermined amount and locked in a second position where the pressure upon the heel is suitable for the nailing operation without being excessive or apt to crush the last. As a suitable means to this end, I show a spring bar 13 with a catch 14 at its lower end equipped with two ledges 15, 16, one above the other in step relation, the distance between these ledges determining the extent of the final compression of the heel after its initial adjustment against the nailing plate. These locking ledges are adapted to engage underneath a fixed abutment 17 secured to or forming part of the block 2. The spring locking bar 13 is adjustably held to the head 5 by elongated slot and bolt connections 18, the inter-engaging surfaces being preferably serrated as seen at 19. The lower end of the catch head 14 is beveled as seen at 20 to be engaged by the end of a lever 21 fulcrumed at 22 with an operating handle 23 for tripping the lock, this lever being normally held in inoperative position as shown by a spring

24. Suitable means for holding the head 5 from turning is provided, this being shown as a lug 25 at the back of the sleeve 4 carrying a stud or post 26 slidably mounted in 5 block 2.

Referring now to the means for supporting the shoe in operative relation to the nailing mechanism, I provide a jack which may be one such as is shown and described 10 in my said application, Serial No. 836,014, said jack being provided with suitable heel and toe rests, and being capable of vertical adjustment by means of the handle 39 and coacting gears 34, 35. As the jack forms no 15 part of the present invention, and it is obvious that any jack capable of vertical adjustment may be used, further detailed description is deemed unnecessary.

It will be understood that in use the 20 handle 7 will be operated to depress the head 5 carrying the nailing plate 6 against the tension of the spring 10 until the first locking notch 15 snaps under the abutment 17. The handle 39 engaging the gear 35 will 25 then be swung a distance sufficient to bring the heel, as it is set in place on the shoe resting on the jack, into proper relation or preliminary pressing engagement with the nailing plate 6. The amount of swing of 30 said handle 39 and gear 35 for this purpose varies with the different heights of heels and sizes and styles of shoes. Thereupon the heel being brought to the proper position by operation of the handle 39, the power head 11 35 descends to prick the holes, at the same time pressing down upon the nailing plate 6 to give the final compression to the heel, and as this occurs, the second step or notch 16 of the locking bar 13 snaps in place under 40 the abutment 17 holding the nailing plate down to keep the heel properly compressed as the nails are driven. In these operations 45 it will be noted that it is possible to determine the extent of secondary or power compression of the heel with exactness, since the preliminary compression, as effected by the operation of the jack handle 39, is to a definite and predetermined extent, and of course 50 the extent of movement of the power head is likewise a definite invariable quantity.

While I have shown one form of locking means, the same may be changed without departing from the essential principle of operation and I therefore refer to the appended 55 claims rather than to the foregoing description to indicate the scope of the invention.

Having described my invention, what I claim as new and desire to secure by Letters Patent is:

1. A heel nailing machine, comprising a 60 nailing plate mounted to move vertically and equipped with means for normally holding it yieldingly elevated, a two-step lock for locking said plate in either a preliminary or a final lowered position below its normal position, and a jack post support having means to adjust the heel of a shoe positioned thereon in operative relation to said nailing plate when locked at the first step of said two-step lock for the purpose stated. 65

2. A heel nailing machine, comprising a nailing plate mounted to slide vertically and equipped with means to hold it normally yieldingly elevated, a two-step lock connected to control said plate and adapted to 70 hold it in either of two lowered positions a relatively short distance apart, a jack post, and an operating device for adjusting said jack post upward by predetermined and variable amounts at a single movement of said 75 operating device to bring a heel on a shoe resting on said jack in operative relation to said nailing plate in its first or preliminary lowered position for the purpose stated.

3. A heel nailing machine, comprising a 80 head mounted to slide vertically with a spring to hold it normally elevated, a nailing plate carried by and projecting from said head, a spring bar carried by said head having two-stepped shoulders, a fixed abutment to cooperate with said shoulders for holding the head in either a preliminary or a final lowered position at will, means for holding a shoe with a heel set thereon in 85 operative relation to said nailing plate when in preliminary lowered position, and an operating device adapted to raise said jack post by variable amounts at a single movement to bring shoes with heels of different heights in proper relation to said nailing 90 plate. 95

4. In a machine of the class described, a vertically movable nail plate carrying head, normally elevated and yieldingly supported, carrying one member of a two-stepped locking means, a fixed member adapted to co-act with said first member, means to manually cause a preliminary first step engagement of the locking means, and power applied means to thereafter cause final second step engagement of said locking means. 105

In testimony whereof, I have signed my name to this specification, in the presence of two subscribing witnesses.

WILLIAM E. SCARLETT.
